RIBBON

Morris Katz, Bronx, N. Y.

Application June 12, 1937, Serial No. 147,862

3 Claims. (Cl. 41—21)

This invention relates to ribbon designed to tie as well as decorate various kinds and classes of packages; and the object of the invention is to provide a ribbon of the character described consisting of two or more strips of sheet material arranged directly one upon the other and the side edges of which are foldable inwardly upon one surface of the strip to reinforce and strengthen the edges as well as to provide a finish for said edges; a further object being to provide a ribbon of the character described wherein at least one of the strips, preferably the outer strip, is composed of transparent cellulosic material, such for example as "Cellophane", so as to give to the finished product a sheen or lustre as well as a smooth surface; a further object being to provide a ribbon of the character described wherein the folded edges will produce, in the use of different colored strips, two or more toned effects to enhance the appearance of the resulting product; a further object being to provide means for characterizing or ornamenting one of the strips to produce on the finished product a predetermined design or ornamentation; a still further object being to provide a ribbon of the character described wherein one of the strips is crinkled or creased to produce what may be termed iridescent or substantially iridescent effects in the finished ribbon; and with these and other objects in view the invention consists in an article of manufacture of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view of a part of the ribbon showing one method of constructing the same.

Fig. 2 is a section on the line 2—2 of Fig. 1.

Fig. 3 is a view similar to Fig. 2 showing a modification.

Fig. 4 is a view similar to Figs. 2 and 3, showing another modification.

Fig. 5 is a view similar to Figs. 2, 3, and 4, showing still another modification.

Fig. 6 is a perspective view of a modified form of ribbon which I employ.

Fig. 7 is a view similar to Fig. 6, showing another arrangement of the teachings disclosed in Fig. 6, and,

Fig. 8 is a view similar to Figs. 6 and 7, showing another form of construction.

In the construction shown in Figs. 1 and 2 of the drawing, I have shown a ribbon which is composed of inner and outer strips 10 and 11. These strips are arranged one upon the other and the side edges thereof are foldable inwardly upon the surface of the strip 10 as seen at 10a and 11a. The folds, 10a, 11a, form what may be termed flanges and in addition provide a greater density of color to the side edge portions of the ribbon, especially when both of the strips 10 and 11 are composed of transparent or substantially transparent material and of one color, or of two different colors. For example, if the inner strip 10 were red and the outer strip 11 were colorless material a deeper shade of red would be provided along the edges of the ribbon than in the central portion thereof intermediate the flanges. At this time it will be understood, however, that in some cases and with the several forms of construction later described, the inner strip may be composed of an opaque or substantially opaque material which may be solid or of openwork structure depending upon whether or not designs or ornaments are desired and such inner opaque or substantially opaque strip may be composed of paper, a suitable fabric of the silk, cotton, rayon, or other type in which latter cases greater body and greater strength will be provided for the finished product.

In Fig. 3 of the drawing, I have shown a slight modification of the structure shown in Fig. 2, wherein the outer strip 11 is of greater width than the inner strip 10 so as to provide supplemental flanges 11b, which extend from the edges of the flanges 11a and preferably rest within the flanges 10a of the strip 10, as will be clearly seen in Fig. 3 of the drawing, and with this construction a still greater depth in color will be provided at the flange portion of the strip, especially when the strip 11 is composed of colored material. In this connection it will be apparent that in some cases, the inner strip 10 may be wider than the outer strip 11, and have double folded flanges, and especially when said inner strip is of colored material and the outer strip colorless.

As a further modification of the structure shown in Fig. 3 of the drawing, I have shown in Fig. 4, a shorter flange 11c extending from the flanges 11a, so as to produce a three toned effect rather than a two toned effect, which would prevail with the structure shown in Figs. 2 and 3. That is to say, that portion of the complete ribbon where the flanges 11c are located would be

of a darker color than that portion outwardly of the flanges $11c$, whereas the portion of the ribbon intermediate the flanges will be of a still lighter color producing a three toned effect. It will also appear that with the structure shown in Fig. 4, the same alternate arrangement described with respect to Fig. 3 may be provided; that is to say, the additional fold on the flange $10a$ instead of on the flange $11a$.

10. In Fig. 5 of the drawing, I have shown another adaptation of the invention, wherein the ribbon is constructed from three strips of material 12 , 13 and 14 ; the strip 12 being the inner strip, the strip 13 the outer strip, and the strip 14 the intermediate strip. The side edges of all of these strips are folded inwardly to form flanges $12a$, $13a$, and $14a$, which are arranged upon the surface of the strip 12 , the same as in the construction shown in the other figures. With this construction both the inner and the outer strips 12 and 13 may be composed of cellulosic material such as "Cellophane", and this may also be true of the strip 14 ; and on the other hand, the strip 14 may be composed 25 of the other materials heretofore referred to.

In Fig. 6 of the drawing, I have shown another adaptation of my invention which is applicable to any of the forms of ribbon shown in Figs. 1 to 5 inclusive; but is shown, for illustrative purposes, applied to a ribbon similar to that shown in Figs. 1 and 2. With this construction, the inner strip 15 is plain or uncharacterized except as to the inclusion of a predetermined color whereas the outer strip 16 which 30 may be transparent or of a predetermined color is provided with suitable marks or ornamentations as indicated at 17 to give predetermined design or character to the finished ribbon. These markings may be in the form of printed characters or the strip may be perforated in predetermined designs so that the contrasting color of the inner strip 15 will appear clearly through the perforations or cutouts. The strips 15 and 16 both have the inturned edges $15a$, $16a$, as in 35 the other forms of construction.

In Fig. 7 of the drawing, I have shown a reversal of the structure shown in Fig. 6; that is to say, the inner strip 18 is provided with ornamentations, characters, marks, or perforations 19 , whereas the outer strip 20 , is uncharacterized except as to color. In this connection, it will be understood that with the structure shown in Figs. 6 and 7, any desired material may be employed in the respective strips but it is preferred that at least one of the strips be composed of the cellulosic material to provide the desired lustre and sheen which gives richness to the resulting product.

In Fig. 8 of the drawing, I have shown another modification wherein one of the strips employed in the construction of a ribbon, the inner strip 21 in the construction shown, is composed of crinkled, creased, or folded material; and the other strip 22 , the outer strip in the construction shown, is composed of plain, non-crinkled transparent and suitably colored material. This construction is applicable to any of the forms of construction shown in Figs. 1 to 7 inclusive; and with regard to Figs. 6 and 7 would preferably be applied to strips 15 and 20 respectively; any suitable inturned or foldable flanges or edges $21a$, $22a$, being provided. The strips 18 and 20 also include the flanges $18a$ and $20a$.

76. The structure shown in Fig. 8, will produce

what may be termed iridescent or substantially iridescent effects in the finished product. In other words, the lustre or sheen or varied colored effects will be materially enhanced in a 5 tendency to produce other variegated color effects, and in fact designs will prevail. In addition to any other definite ornamentation or design which may be applied to any of the strips employed, I have found from experience and experimentation, that different colored strips may be used 10 one upon the other in which event beautiful lustres are produced in the resulting ribbons. Where ornamentation is employed, it will be understood that one strip may be of a given color with the ornamentation appearing thereon in a 15 contrasting color; and still again the other strip or strips employed in the ribbon may be of a still different color. In this connection, it may also be borne in mind that in referring to the use of the characterized strips, that a combination of printed and openwork designs may be provided, so as to present upon the outer surface of the ribbon the multi-colored effects as will be apparent. To explain the latter, let us assume that a ribbon were printed to represent the green foliage of a poinsettia and the flower of the poinsettia were printed in red giving the two colored effects in the one strip. Then the strip could be perforated centrally of the representation of the poinsettia and an inner yellow strip would show through the outer strip to provide the yellow center for the poinsettia; especially in making ribbon suitable for wrapping Christmas packages. It will be apparent 20 that many other arrangements can be provided 25 in this three colored effect without the necessity of printing one strip in three different colors which of course can be done.

It will also be apparent that in some uses of the invention and especially with structures as 30 shown in Figs. 3 and 4 of the drawing, the inner facing strip may be omitted and the same effect can be produced by simply enclosing narrow strips within the folded flanges $11a$, $11b$, and $11c$. On the other hand with structures 35 such as shown in Fig. 2, narrow strips may be suitably attached to the flanges $11a$ to prevent displacement therefrom. Again, it will appear 40 that the inner strip may be plain and not include the inturned flanges, and the outer strip 45 include flanges overlying the side edge portions of the inner strip. It will also be apparent that one or both of the strips may be treated with a suitable saturant, such for example as glycerine or glycerine and water, to maintain the 50 ribbon in a soft and pliable state, in accordance 55 with the teachings in my prior Patent #2,041,418, in the production of cellulosic cord and twine.

It will be understood that the foregoing illustrations which have been briefly described, are 60 illustrative only of certain basic principles in the construction of ribbon made according to my invention and many variations of these basic principles may be devised in the construction of ribbons suitable for many uses. In this connection, 65 it will be apparent that in utilizing the ribbon as a tying means for packages by merchants, various kinds and classes of advertising matter may be arranged upon the ribbon; or other means of trade marking or identifying the packages 70 tied thereby.

Having fully described my invention, what I claim as new and desire to secure by Letters Patent, is:

1. A ribbon of the class described comprising 75

- inner and outer strips of substantially transparent cellulosic material, said strips being arranged in superimposed relation, the side edges of said strips being folded inwardly upon the surface of said inner strip to form reinforcing edge flanges extending longitudinally of said ribbon, one of said strips being of predetermined color, said colored strip being wider than the other strip and foldably arranged thereon to form narrower flanges on the inner adjacent edges of said first named flanges thereby providing one, two and three layer portions of said colored strip producing a corresponding three-tone color effect in said ribbon.
2. A ribbon of the class described comprising inner and outer strips of transparent cellulosic material arranged one upon the other at least one of said strips having incorporated therewith a saturant adapted to keep the ribbon soft and

pliable, one of said strips being tinted a predetermined color, the edges of said strips being folded inwardly onto the surface of said inner strip to form reinforcing edge flanges, and said flanges, by virtue of the multiple layers thereof being of a deeper shade of color than the rest of the ribbon. 5

3. A ribbon of the class described comprising inner and outer strips of substantially transparent cellulosic material arranged one directly 10 upon the other in abutting relationship, the edges of said strips being folded inwardly onto the surface of said inner strip forming reinforcing edge flanges longitudinally of the ribbon, said outer strip being tinted a predetermined color, and said 15 inner strip being of irregular surface contour providing an iridescent effect in the ribbon when viewed from the outer flangeless side thereof.

MORRIS KATZ.
